UNITED STATES PATENT OFFICE.

HAZEL CRAWFORD WILLETT, OF RHINELANDER, WISCONSIN.

STOCKING PROTECTOR.

Application filed May 18, 1927. Serial No. 192,295.

The present invention relates to improvements in stocking protectors and has for its principal object to provide a simple and efficient device which is adapted to be worn over the stocking and which extends from the shoe to a point within the vicinity of the knee, the protector being formed of thin and transparent rubber, so that the water will not be splashed upon the back of the lady's stocking while walking in rainy or snowy weather.

One of the important objects of the present invention is to provide a stocking protector wherein the same is of such construction as to permit the protector to be readily rolled up, when not in use, means being provided at the top of the protector for receiving and enclosing the rolled portion of the protector whereby to simulate a garter or the rolled top of a stocking, and which rolled protector will be supported on the calf of the leg in an inconspicuous manner.

A further object is to provide a stocking protector of the above mentioned character, wherein means is provided for maintaining the protector in a rolled condition, the same being of such construction as to permit the removal of the protector from the leg of the wearer, whereby the same may be folded or otherwise rendered compact, to permit the placing of the protector within the pocket-book, thus enabling the protector to at all times be at hand, for use whenever necessary.

A still further object is to provide a stocking protector of the above mentioned character which is simple in construction, strong and durable, and further well adapted to the purpose for which it is designed.

Other objects and advantages of the invention will become apparent during the course of the following description.

In the accompanying drawing, forming a part of this application, and in which like reference characters designate like parts throughout the views:

Figure 1 is a side elevation of the stocking protector embodying my invention showing the same in use, a portion of the flap being disposed upwardly to disclose more clearly the securing means, and

Figure 2 is an enlarged detail of the stocking protector, showing the same in its rolled condition and supported on the leg of the wearer at a point below the knee whereby

the same simulates the usual rolled top of a stocking or garter.

In the drawing, wherein for the purpose of illustration is shown the preferred embodiment of my invention, the numeral 1 designates generally my improved stocking protector, the same comprising a tubular body 2, which is formed of thin and transparent rubber and which rubber may be colored if so desired. The body 2 is of such length as to extend from a point adjacent the foot of the wearer to a point within the vicinity of the knee and this is clearly illustrated in Figure 1. By constructing the body 2 of elastic rubber, the same will snugly fit the leg of the wearer. The tubular body is open at its respective ends, and the lower end thereof is shaped so as to fit over the upper of a lady's shoe or slipper, as indicated generally at 3, and for the purpose of further maintaining the lower portion of the body in proper position, it is provided with a strap 4 which extends transversely beneath the instep and this strap is also formed of elastic rubber and is secured at its respective ends to the adjacent sides of the open lower end of the tubular body 2. By arranging the lower portion of the tubular body in this manner, the lower portion of the stocking adjacent the upper of the shoe will be protected against any water splashing on that portion of the stocking.

A relatively wide flap 5 is formed at the upper open end of the tubular body 2 and this flap is turned downwardly and the free edge of the flap is provided with a reinforcing band 6, which is also of elastic rubber. The purpose of this flap will be presently described.

Normally the parts of the protector are arranged as shown in Figure 1 of the drawings and the elastic rubber body will completely protect the stocking from being splashed and stained by the water while the wearer is walking in rainy or snowy weather.

When not in use, the strap 4 is disengaged from beneath the instep portion of the shoe and the stocking protector is then rolled up, so that said rolled body will be disposed beneath the flap 6 and for the purpose of securing the rolled portion of the protector within the flap, I provide the detachable fastening means shown in the drawing, and which consists of a snap fastener of the con-

ventional construction, the head portion thereof being secured to the under side of the flap as illustrated at 7, while the complementary socket portion 8 is secured to the inner side of the body adjacent the lower free edge portion of the flap. The portion of the body to which the socket 8 is attached is reinforced as shown at 9. In this manner the stocking protector when rolled up will 10 provide a small and compact structure, and may be worn on the leg in simulation of the usual rolled top of a stocking and may furthermore serve as a garter for supporting the stocking below the knee.

15 The protector may be entirely removed from the leg when not in use, and may be folded or otherwise rendered compact to permit the same to be placed within the purse or pocketbook so that the protector 20 will, at all times, be at hand for use whenever necessary.

The simplicity of my improved stocking protector enables the same to be readily and easily placed in position and will not present 25 an unsightly appearance when worn as a protector and furthermore when rolled up for disposition on the leg of the wearer, the same will be inconspicuous.

A stocking protector of this character may 30 be manufactured at a very low cost and due to its simplicity will not necessitate the expenditure of any considerable length of time or labor in attaching or removing the same.

35 While I have shown the preferred embodiment of my invention, it is to be understood that various changes in the size, shape and arrangement of parts may be resorted to, without departing from the spirit of the 40 invention or the scope of the appended claims.

What I claim as new is:

1. In a stocking protector of the class de-

scribed, a tubular body adapted to fit snugly on the leg of the wearer, and a flap at the 45 upper end of the body, the body adapted to be rolled up and enclosed within the flap when not in use.

2. In a stocking protector of the class de- 50 scribed, a tubular body adapted to fit snugly on the leg of the wearer, a flap at the upper end of the body, the body adapted to be rolled up and enclosed within the flap when not in use, and means for securing the free edge of the flap to the body to retain 55 the rolled portion of the protector within the flap.

3. In a protector of the class described, a tubular body formed of thin transparent elastic rubber adapted to fit snugly on the 60 leg of the wearer, a flap formed on the upper end of the tubular body and turned downwardly for disposition on the outside of the body, the major portion of the body adapted to be rolled up and housed within the flap 65 when not in use, and means for securing the free edge portion of the flap to the adjacent portion of the body to retain the rolled portion of the body within the flap.

4. In a stocking protector of the class de- 70 scribed, a tubular body formed of thin transparent elastic rubber adapted to snugly fit the leg of the wearer, the lower portion of the body being shaped to fit snugly around the upper of a shoe, a flap formed 75 on the upper portion of the body and turned downwardly for disposition on the outside of the body, the major portion of the tubular body adapted to be rolled up on the leg of the wearer for disposition within the slot, and means for detachably securing the free 80 edge portion of the flap to the adjacent portion of the body to retain the rolled portion of the body within the flap.

In testimony whereof I affix my signature.
HAZEL CRAWFORD WILLETT.
